UNITED STATES PATENT OFFICE.

NATHAN HATCH, OF ALBANY, NEW YORK.

UNION SUIT.

1,100,657.

Specification of Letters Patent. Patented June 16, 1914.

Application filed January 30, 1914. Serial No. 815,372.

To all whom it may concern:

Be it known that I, NATHAN HATCH, a citizen of the United States, and a resident of Albany, county of Albany, and State of New York, have invented certain new and useful Improvements in Union Suits; and I do declare the following to be a full, clear, and exact description of the invention, such as will enable others skilled in the art to which it appertains to make and use the same, reference being had to the accompanying drawings, and to the letters and figures of reference marked thereon, which form part of this specification.

15 The invention relates to an article of wearing apparel, more particularly to union undergarments for men, women and children.

One of the objects of the invention is to 20 construct a union suit to fit the body of the wearer perfectly and securely and to make it very easy to put on and take off the person of the wearer.

Another object is to construct a garment 25 in which it is not necessary to provide the objectionable lines of buttons and button-holes or securing means which are usual in men's garments, which extend from the neck thereof to the crotch, thereby preventing the 30 objectionable gaping due to the button structure.

Another object is to provide the union undergarment with the single fastening means arranged in the front thereof at the 35 center of the chest.

The garment is especially useful for the purpose of protecting the body of the wearer, yet it is so constructed that it is very desirable for the use of women inasmuch as the lines of the neck portion may be so laid as to be used by women when they desire to wear outer garments which are open at the neck and chest. The construction is also very desirable for women's 40 garments inasmuch as the fastening means are provided at or about the center of the chest and the front portion of the body part of the garment is so constructed as to fit the bust nicely and is therefore adapted for 45 women's wear as will be readily understood from the following description.

Other objects will appear from the following description and claims.

The garment is to be put on the body of 50 the wearer by inserting the legs into the leg portions in the usual way, and then the

upper or front portion of the garment drawn up around the body of the wearer. The arms are then inserted, and the three front flaps are then secured together by 55 fastening means at or about the center of the chest.

Referring to the drawing forming part of this specification: Figure 1 is a view of the front of the garment embodying my invention, the garment being shown in its closed position. Fig. 2 is another view of the front of the garment embodying my invention, the garment being shown with the front flaps open. Fig. 3 is also a view of 70 the front of the garment as especially adapted for women's wear. In the detailed description of the same, similar reference characters indicate corresponding parts.

The garment may be made of either woven 75 or knitted fabric, and except for the features of construction which form my invention, it is made in the usual way, namely, the leg portions may be long or short, the arm portions long or short, the leg and arm ends are 80 ribbed and finished as usual and the border about the neck and body flaps are finished in the usual way. The garment may also be provided with an open and over-lapping fly construction and it is provided with the usual 85 open and overlapping substantially longitudinal opening in the seat portion thereof. The seat portion is constructed in the usual way by means of two substantially triangular patterns or inserts which are secured to 90 the garment and to each other, a fastening means being placed upon the outer edge of one of the inserts and another fastening means to coöperate therewith secured to the rear of the garment. 95

Referring to the drawings: A represents the body portion of the garment, B the leg portions, C the center front flap, D one side flap, E the other side flap.

a is the fastening means upon the front 100 flap, and b the means on the two side flaps.

My invention is particularly embodied in the following construction: From points 1 and 2 situated upon opposite sides of the body portion at or about the waist line, and 105 extending upward in a straight or curved line to the point 3 is a front flap portion. Two side flaps forming the remainder of the front portion of the garment extend respectively from points 4 and 5 on the side of the 110 garment also at or about the waist line in a substantially straight or curved line to

points 5 at or about the center of the chest portion and continue on a straight or curved line to the back of the neck at 6. Each of the flaps formed as above described is therefore 5 substantially triangular in shape and may be so defined. The edges of the center and side flaps are overlapped, so as not to expose the body of the wearer and are finished in a manner to prevent gaping. The three flaps 10 constituting the front portion of the body are brought together and secured the one to the other at their apices by means of the button *a* and button holes *b*.

While I have shown a button on one portion 15 of the garment and button holes on the other, it is evident that the positions of the two may be reversed. The buttons may of course be made of any suitable material and may be formed of a knot similar to the usual 20 "Turk's head" knot of well known construction. The free ends of the flaps may also be secured together by means of a removable button of the ordinary double head and shank type inserted in button-holes provided 25 in each of the flaps; or by a pin secured thereto.

As shown in Fig. 2, several button-holes usually two in number may be made in the 30 apex of the center flap for the purpose of adjusting the body length of the garment.

The cut of this garment, providing the 35 opening from the waist line up to a point approaching the neck, lends itself to the natural lines and curves of the human body, and it is by reason of this fact that any gaping or sagging of the suit is effectually prevented.

I have illustrated and described the embodiment of my invention which I believe to be the one best subserving the object 40 which I have in view, nevertheless the invention is not restricted in details except as definitely expressed in the claims.

Having now described my invention, what I claim as new and desire to secure by Letters Patent is:

1. A union suit the entire front of the body portion thereof above the waist line being normally open from the neck to points upon each side at or about the waist line, 50 the said opening being bounded at the bottom and sides thereof by three substantially triangular flaps and a single fastening device for detachably securing the apices of the triangular flaps together. 55

2. A union suit the entire front of the body portion thereof above the waist line being normally open from the neck to points upon each side at or about the waist line, the said opening being bounded at the bottom 60 and sides thereof by three substantially similar triangular flaps and a single co-acting fastening device for detachably securing the apices of the triangular flaps together at a point substantially at the center of the front 65 body portion.

In witness whereof I have hereunto set my hand at the borough of Manhattan, city and State of New York, this 24 day of January, 1914.

NATHAN HATCH.

In presence of—

JOHN J. RANAGAN,
FRANK EUFEMIA.
